COOLING SYSTEM.

Application filed August 3, 1921. Serial No. 489,464.

This invention relates to systems for removing excess heat from the circulating or cooling fluid used in connection with an internal combustion engine, and more particularly to systems of this kind in which the water or other cooling fluid is permitted to boil in the engine jackets and in which the vapor only is passed into a radiator or the like and condensed, the condensate being returned to the circulating fluid.

The objects of the invention are to provide a system of this kind in which the usual circulating pump for the cooling medium is eliminated; also to provide a system of this kind in which the cooling liquid circulates in a circuit which is entirely separate from the circuit in which the vapor or steam and condensate are caused to flow; also to provide means of improved construction for returning the condensate to the cooling medium; also to provide a radiator of improved construction for use in connection with a cooling system of this kind; also to improve cooling systems of this kind in other respects hereinafter specified.

In the accompanying drawings:

Fig. 1 is a side elevation partly in section of an engine provided with a cooling system embodying the invention.

Fig. 2 is a side elevation of an engine provided with a cooling system of slightly modified construction.

Fig. 3 is a similar view showing the arrangement of the parts when the radiator is located above the engine.

Fig. 4 is a fragmentary top plan view of a radiator of the kind shown in Fig. 2.

A represents an internal combustion engine having a plurality of cylinders provided with jackets for a cooling medium such as water or other liquid. The cooling medium carries heat from the cylinder walls and different means have heretofore been devised for removing excessive heat from the cooling liquid. In engines as commonly built, a water circulating system including an air cooled radiator is used and the water passes through the radiator and back to the jackets of the engine. Generally a circulating pump is used to ensure a constant flow of cooling medium through the cylinder jackets, although this pump is not essential in some engines which are constructed to cause a circulation of the cooling liquid by a thermosiphon system. This system operates due to the difference in

gravity between the hot liquid in the water jackets and the cooled liquid in the radiator, the heavier cool liquid flowing downwardly and the hot liquid in the jackets upwardly, thus producing a circulation. If, however, the liquid in the radiator should not be cooled and should be of approximately the same temperature as that in the engine jackets, no circulation would be produced by the thermosiphon system. In cooling systems of the radio-condenser type, the liquid is circulated by means of a pump without passing through a radiator and only the vapor arising from the heated liquid is passed through the radiator, where it is condensed, the condensate being returned to the cooling liquid. In this last described system, a circulating pump has invariably been used for circulating the liquid through the jackets of the engine.

I have found that it is possible in a system in which the vapor only passes through the radiator, to provide a circulation of the hot liquid through the engine, without the use of a pump. This can be accomplished by providing passages of comparatively large cross sectional area for the liquid, so as to reduce the resistance to the flow of the liquid, and the currents producing the circulation of the liquid are set up due to the ebullition or boiling of the liquid in the engine jackets. These ebullitional currents are probably due to the presence of small particles of vapor in the boiling liquid in the engine jackets, which naturally rise violently on account of their buoyancy and produce a positive and forcible circulation. These ebullitional currents produce a more rapid flow of the circulating liquid than is produced under the most favorable conditions in a thermosiphon system, the flow being rapid enough to produce an agitating action like that produced when a pump is used, even though the temperature of the liquid in both columns is approximately the same, since the heat lost in the return column is negligible.

In the embodiment of the invention shown in Fig. 1, the liquid from the upper ends of the water jackets is discharged into a passage b connecting with the jackets of all of the cylinders and this passage terminates in a vapor or steam chest B in which the steam or vapor may escape from the water and collect in the space in the chest above the liquid level. The vapor or steam chest

B is connected with a downwardly extending return tube or passage b' of comparatively large cross sectional area terminating in the chest B below the water level, and 5 this passage in turn connects with a water inlet tube or pipe b^2 which terminates in the lower portions of the engine jackets. The return column of liquid in the upright tube b' being freed of steam or vapor, is 10 heavier than the liquid in the engine jackets, so that the liquid in the tube b' flows downwardly and that in the engine jackets flows upwardly, and the passages b and b^2 and the steam or vapor chest form connections 15 between the engine jackets and the tube b' , thus completing a circuit in which the cooling liquid may be circulated with considerable violence by the force of the ebullitional currents. By means of this arrangement 20 a comparatively strong current is produced which provides a very reliable circulation of the cooling medium through the engine jackets. In order to produce rapid and violent ebullitional currents, it is desirable 25 that the jackets of the engine be so designed as to produce as little resistance to the flow of the liquid as is possible and care must be taken that the jackets are provided with no pockets or recesses in which vapor may 30 collect. By means of this arrangement, the usual liquid circulating pump can be eliminated, thus saving not only the expense of the pump but also the power necessary to drive the same. 35 In order to condense the vapor or steam collecting in the upper portions of the steam chest B, an air cooled radiator C of any suitable or desired construction is preferably employed, and in the construction 40 shown in Fig. 1, the upper tank c of the radiator is connected with the vapor or steam chest B by means of a tube or other suitable passage c' . The steam passing downwardly into the radiator is condensed 45 in the radiator and the condensate flows downwardly into the lower tank c^2 of the radiator. The condensate is then returned to the cooling liquid through a pipe D, the upper or discharge end of which terminates 50 in the steam or vapor chest B above the level of the liquid therein. Any suitable means for returning the condensate to the cooling liquid may be employed, a pump d being used in the construction shown in 55 Fig. 1. By returning the condensate into the steam or vapor chest B above the liquid level therein, the circuit through which the vapor and condensate pass is entirely separate and distinct from the circuit in which 60 the cooling liquid circulates, so that none of the cooling liquid can enter into the radiator except in the form of vapor. This eliminates the need for the usual check valve or pressure employed in systems heretofore used and which has been found objection- 65

able and unreliable in operation. The liquid level in the steam chest B may be controlled in any desired manner to prevent liquid from entering into the pipe D, a filling tube or pipe b^3 being provided for this 70 purpose, which is connected with the steam chest and which is open at its upper end. This pipe serves the two-fold purpose of preventing the liquid from rising above the desired level in the steam chest and is also 75 used for supplying cooling liquid to the engine.

In the radiator C it is necessary to provide means for permitting the steam passing into the upper tank of the radiator to 80 displace the air in the radiator and for this purpose the lower tank is preferably provided with a discharge valve E which is normally closed by means of a ball e or the like but which may be opened by pressure 85 in the lower tank. Consequently when the steam presses the air downwardly through the radiator, the air will be discharged from the valve E. After the air has been discharged, no further discharge of vapor or 90 liquid will take place since pressure in the system will be relieved by the condensation of the vapor in the radiator. If for any reason, however, the vapor pressure in the system becomes excessive due to failure of 95 the radiator to condense all of the vapor or for any other reason, the valve E also acts as a safety valve and will discharge sufficient vapor to relieve the pressure in the cooling 100 system. The valve E is located well above the liquid level in the tank D so that in case of excessive pressure, vapor, and not liquid, will be discharged through the valve E, thereby conserving the supply of liquid in 105 the system.

In the construction shown in Fig. 2, F represents the engine and f the vapor or steam chest. The circulation of water due to ebullitional currents takes place through 110 a downwardly extending pipe f' connected with the vapor chest f below the liquid level therein, and a pipe f^2 leading to the lower portions of the engine jackets. The vapor from the chest f passes into a pipe f^3 by 115 means of which it is conducted to the upper portion of a tank g arranged at the base of a series of radiating tubes or passages G. In this construction, the vapor instead of passing downwardly through the radiator 120 as in the construction shown in Fig. 1, is admitted to the lower portion of the radiator and is adapted to rise in the radiator until condensed. In this construction it is not necessary to provide the radiator with the usual upper tank and for this purpose the upper ends of the vapor passages or tubes of the radiator are preferably partly closed in any suitable manner, for example as shown in Fig. 4, a small opening g' being 125 preferably provided for each tube or

passage. Through these small openings in the tube the vapor escapes with difficulty in case the radiator capacity is too small, thus relieving any excessive pressure, so that as little of the cooling medium as possible is wasted. In a system provided with a radiator of this kind, the pressure in the system under ordinary operating conditions is atmospheric and air may be displaced from the radiating tubes as the vapor in the radiating tubes increases. With this construction, the escape of liquid through the discharge holes is practically eliminated.

10 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

15 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

20 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

25 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

30 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

35 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

40 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

45 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

50 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

55 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

60 The condensate collects in the bottom of the lower tank *g* of the radiator and is returned to the circulating liquid by means of a pump *H* which causes the liquid to flow upwardly through a pipe or tube *h* into the steam or vapor chest *f* above the level of the liquid therein. Water may be supplied to the system through a tube or pipe *h'* which also prevents the liquid in the system from rising above the desired level.

divided into two separate circuits, which has the advantage of preventing the liquid from flooding the radiator and thus interfering with the operation of the system, and also of eliminating the use of check valves or other means heretofore used, for keeping the circulating liquid out of the radiator. By means of the construction shown in Figs. 2 to 4 inclusive, the construction of radiators used in connection with systems of this kind is facilitated since the upper tank usually employed may be dispensed with, thereby saving the cost of the upper tank.

I claim as my invention:

1. In a cooling system for an internal combustion engine, having jackets for a cooling liquid which are in communication at their upper portions, a circuit for the cooling liquid of very low friction head, of negligible cooling capacity, and of very low static head in series with and including said jackets in which circulation is effected only due to heat imparted to the cooling liquid in the engine jackets, a vapor chest which is partially filled with liquid and in which vapor collects above the liquid level therein, the part of said chest below the liquid level being included in said circuit, and a downflow passage of relatively large cross section, conducting liquid from said chest to the lower portions of said jackets, a condenser to one end of which the vapor collecting in said chest above the liquid level therein is admitted, and a vent for discharging from the other end of said condenser the air displaced by the vapor.

2. In a cooling system for an internal combustion engine having jackets for a cooling liquid, a passage immediately above said jackets and connecting the same, a vapor chest whose lower portion contains cooling liquid, said jackets, said passage and said lower portion of the chest forming a series circuit for the cooling liquid, whose resistance is reduced to a minimum firstly by the use of connections of relatively large cross sectional area and secondly by making the liquid head above the jackets very low and equal to or less than the sum of the liquid heads in said passage and said chest, whereby a positive circulation is set up by the ebullitional currents in the jackets, a radiator which is normally empty for condensing the vapor collecting in above mentioned chest above the liquid level therein at atmospheric pressure, and a vent in said radiator which is placed in the end of said radiator opposite to the end at which vapor enters the radiator.

The cooling system described has the advantage of eliminating the necessity of using the ordinary circulating pump due to the fact that the necessary circulation of the cooling liquid is obtained by ebullitional currents. By returning the condensate to the vapor or steam chest above the level of the liquid therein, the cooling system is
